UNITED STATES PATENT OFFICE.

RICHARD W. KAUCHER, OF READING, AND JOHN WALTER BARR, OF SINKING SPRING,
PENNSYLVANIA.

FIRE DOOR.

1,425,973.

Specification of Letters Patent. Patented Aug. 15, 1922.

Application filed July 28, 1920. Serial No. 399,515.

To all whom it may concern:

Be it known that we, RICHARD W. KAUCHER and JOHN WALTER BARR, citizens of the United States, residing at Reading, in the county of Berks and State of Pennsylvania, and Sinking Spring, in the county of Berks and State of Pennsylvania, respectively, have invented certain new and useful Improvements in Fire Doors, of which the following is a specification.

This invention relates to fire doors and operating mechanism for same, and particularly to fire doors for use with locomotives, or in connection with other fire boxes where there is a source of pressure supply convenient.

It is well recognized that considerable difficulty is encountered by firemen, and locomotive firemen in particular, in operating the fire door to shovel in coal, because both hands of the fireman are needed for the manipulation of his shovel, and it is desirable that the fire door be kept closed under ordinary conditions as much as possible. It will be seen that when the fireman has to open the door by hand to shovel in the coal, he will not be apt to close it after each shovelful, but will allow it to remain open until he has completed stoking, and it is one of the objects of this invention to provide a fire door which may be opened by pressure of the fireman's foot upon an appropriate lever, and which will automatically close upon removal of his foot from such lever, thus leaving both hands free to manipulate his shovel.

Another object of the invention is to provide a fire door having power-operated means with manually operable means, such manually operable means capable of manipulation independently of the power-operated means and including a latch mechanism for holding the door in open position when desired.

A still further object of the invention is to provide a mechanically or manually operated fire door of such rugged construction and so simple in its mode of operation as to be capable of withstanding the rough treatment to which it is almost certain to be subjected in use.

Another object of the invention is to provide a power operated door with means for cushioning its opening and closing move-

ments to prevent slamming and consequent probable injury.

The invention consists in a fire door provided with a mounting or door-frame adapted to be positioned over the fire door opening of the boiler fire box, this mounting being provided with stops for properly positioning the door when closed, and having bosses to which may be attached the operating parts of the door, as will be hereinafter described, a door mounted for oscillatory movement from closed to open position and vice versa, power operated means for opening and closing said door, and manually operable means including a latch member for opening said door and holding it in open position, said latch member so arranged as to be inoperative when the door is actuated by the power mechanism, all as we will proceed now to explain and finally claim.

In the accompanying drawings illustrating the invention, in the several figures of which like parts are similarly designated, Figure 1 is a front elevation and partial section of the door and its mounting and operating mechanism, and showing in dotted lines the full open position of the door when operated by hand and when operated by the power mechanism, respectively. Fig. 2 is a detail central longitudinal section through the power cylinder, taken in a plane at right angles to that in which the section in Fig. 1 is taken. Fig. 3 is a section taken in the plane of line 3-3, Fig. 1, showing the latch mechanism. Fig. 4 is a side elevation of the control valve and its actuating lever. Fig. 5 is a section taken in the plane of line 5-5 of Fig. 4.

Referring more particularly to the drawings, we provide a mounting or door-frame 1, having elongated bolt openings 2 through 95 which pass the bolts for attaching the mounting or door-frame to the boiler back-head, and this door-frame is provided with an offstanding lip 3 and a stop 4; and a boss 5, provided with a seat 6 to which is attached the power cylinder, later described; and a bearing-face 7, to which is attached the projection 8 of the door 9 by means of a suitable pivot bolt and nut 10 and 11, respectively. This manner of mounting the door permits of its oscillation from closed to open position and vice versa across the face of the door-frame.

Preferably extending upwardly from and formed as a part of the door-casting is a member 12 to the back of which is attached a suitable counterweight 13 provided with 5 a cut-out portion 14, the weight being connected with member 12 by means of a bolt and nut 15 and 16, respectively, whereby the weight may be rotated in order to adjust its cut-out portion to provide a proper 10 counterbalancing for the door.

It will be understood that the door is of the usual type having a front-plate 17 and a back-plate 18, the two being strengthened and alined by means of posts 19, and both 15 plates being provided with ventilating perforations 20 and a peep-hole 21.

Mounted upon the seat 6 is the power cylinder 22, as described, provided with a piston 23 having a concentric longitudinal 20 extension 24 slidably fitted in a guide 25 of the cylinder, and this extension is provided with an elongated socket chamber 26 in which fits the ball-shaped end 27 of a connecting link 28, the other end of which 25 is socketed in and pivoted to the fire door by means of a socket 29 and a bolt 30 passing therethrough and through the end of the link 28. It will thus be seen that the connecting link 28 is fixed to the door but is 30 free to slide in the elongated socket chamber 26. Pivoted between ears 31 on the face of the door by means of a pin 32 is a combination handle and latch mechanism 33, one end 34 of which is turned inwardly and 35 passes through an enlarged opening 35 in the door with a loose fit, the extremity of this end being cut off at an incline for a purpose hereinafter explained. The inward motion of this end is limited by the stop 40 36 which abuts against the face of the door, all of which is clearly shown in Fig. 3. It will be understood that when the door is operated by hand the latch will be grasped and the door raised to position A, shown in 45 dotted lines, and this raising will cause the inclined end of the latch to ride over the inclined face 37 of the door-frame and snap into the socket 38 adjacent thereto, whereby the door is held in its open position.

50 The cylinder 22 is provided with a combination inlet and exhaust port 39 formed with a plurality of openings alined longitudinally of the cylinder and graduated as to size, and to this port is connected a pipe 55 40 which runs to a port 41 of the control valve mechanism 42. This control valve mechanism comprises a casing provided with a central bore 43, having inlet and exhaust valve seats 44 and 45 at its opposite ends, 60 and in this bore are positioned an inlet valve and an exhaust valve 46 and 47, adapted to coact, respectively, with the seats above mentioned, these valves being provided with finned extensions 69, 70, as shown, whereby 65 the passage of air through the bore is per-

mitted. The inlet valve 46 has an extension 48 slidably mounted in a cap 49 which closes the end of the valve-casing, and this cap is provided with a vent-hole 50 which prevents the trapping of air behind the extension 48. The valve 46 is normally held to its seat by means of a spring 51, as shown.

The exhaust valve 47 is provided with a stem 52 passing through a cap 53, its end contacting with an adjustable threaded pin 54 mounted in one end of a lever 55 pivoted at 56 to arms 57 formed on the valve-casing, the other end of this lever being provided with a pedal 58 by which the fireman may operate the valve by the pressure of his foot 80 thereon. At the lower extremity of the valve-casing are provided a plurality of exhaust ducts 59 communicating with the valve-chamber 60, and the upper portion of the valve-casing is provided with an inlet 85 opening 61 communicating with a valve-chamber 62 and adapted to be connected with a suitable source of air or the like under pressure, by means of a pipe 63. When the device of the invention is used with locomotives, the pipe 63 may be and preferably is connected with the main air pressure tank.

Referring to Fig. 2, it will be seen that the cylinder 22 is provided at its end 64 95 with a plug 65 having formed therein a plurality of longitudinally alined vents hereinafter more particularly referred to.

In operating the fire door by means of the power operated mechanism, it will be seen that foot pressure upon the pedal 58 will elevate the end of the lever 55 which carries the pin 54 and cause this pin to raise the stem 52 of the exhaust valve 47 and seat the exhaust valve, at the same time through the 100 cooperation of the finned extensions of the valves raising the inlet valve 46 off of its seat against the pressure of the spring 51 and allowing air to enter the chamber 62 through pipe 63 and pass by the valve 46 and 105 through the port 41 and pipe 40 into the cylinder 22 through the openings of the port 39, whereby the piston is moved forward in the cylinder to its extreme outward position as shown in dotted lines, thereby acting 110 upon the connecting link 28 to oscillate the door 9 upon its pivot 10 to the open position shown in dotted lines at B. By reference to Fig. 2, it will be seen that the openings in the plug 65 are graduated as to size in 115 such manner that the air trapped in that end of the cylinder as the piston moves outward will escape rapidly through the first opening, with less rapidity through the second opening, and very slowly through the 120 last opening, whereby the movement of the piston at the extreme end of its outward stroke is materially cushioned by the trapped air, and the slamming open of the door is prevented.

When the pedal 58 is relieved of the pressure of the operator's foot, the spring 51 will force the inlet valve 46 to its seat and through the finned extensions of the valves 5 will open the exhaust valve 47, thereby allowing the air in the rear end of the cylinder 22 to escape through the graduated openings of the port 39 first rapidly and then slowly, substantially in the same manner as that described with reference to the openings in the plug 65, and through the pipe 40, port 41, bore 43 and exhaust ports 59 to the atmosphere, thus allowing the door to close, its closing being cushioned in the same manner as its opening, as described. The door in its completely closed position will abut against the stop 4 and its notch 66 will abut against the side of the lip 3, the edge of the lip projecting outside of the 20 door and preventing any movement of same away from the door-frame.

As hereinbefore pointed out, it will be seen that the power operated mechanism does not open the door to such an extent as 25 to cause the latch member 33 to engage its seat 38, and hence the mere releasing of the lever 55 will allow the door to close.

When the door is operated by hand, it will be apparent from the construction shown 30 that the operator need not exert any more force upon the door than that which is absolutely necessary to overcome its counterbalanced weight, for the reason that the ball-shaped end 27 of the connecting link 28 is 35 free to slide outwardly in the socket chamber 26 whereby the manual moving of any of the power-operated parts is unnecessary.

The device may be provided with a suitable oil hole 67 by means of which oil may 40 be conducted to the pivot of the door, and as is customary, the piston 23 may be provided with the usual piston rings 68.

It is to be understood that we do not consider our invention as limited to the specific 45 details of construction and arrangement of parts herein shown and described, as it is obvious that various changes may be made therein without departing from the spirit of the invention or the scope of the following 50 claims.

What we claim is:

1. In a fire door, a door-frame, a door 55 pivotally mounted thereon, means connected with said door and operable to open the same, means on said frame for limiting the closing movement of said door, and additional means on said frame for holding said

door in contact with said frame when in closed position.

2. In a fire door, a door-frame, a door 60 pivotally mounted thereon, means connected with said door and operable to open the same, means on said frame for limiting the closing movement of said door, and additional means on said frame for holding 65 said door in contact with said frame when in closed position and forming an additional stop for said door.

3. A fire door comprising a door frame having an opening, a closure member for 70 said opening pivoted adjacent thereto, a catch upon said frame, a latch carried by said closure adapted to coact with said catch when said closure is manually moved to substantially the extent of its travel and 75 power operated means limited to opening said closure to a position short of operation of said latch.

4. In a fire door, a pivot, a door mounted thereon for oscillating movement, power 80 operated means for oscillating said door upon its pivot from closed to open position, said means including a cylinder, a piston mounted therein and provided with a socketed extension and a link pivoted to said 85 door and extending into said socketed extension, and manually operable means for oscillating said door, the link during manual operation of the door sliding freely in said socketed extension independently of 90 said piston.

5. A fire door comprising, in combination 95 with a pivot, a door mounted thereon for oscillating movement, power operated means for operating said door on its pivot from closed to open position, said means including a cylinder, a piston mounted therein, a link pivoted to said door and having a portion 100 abutting against said piston and freely movable therefrom in one direction, means for guiding the movement of said portion from and to its abutting engagement with said piston, manually operable means for oscillating said door, the link during manual 105 operation of the door moving freely under direction of the guiding means independently of the piston.

In testimony whereof we affix our signatures in the presence of two witnesses.

RICHARD W. KAUCHER.
JOHN WALTER BARR.
